UNITED STATES PATENT OFFICE.

WILLIAM T. SMITH, OF PHILADELPHIA, PENNSYLVANIA.

DESIGN FOR FRINGE.

SPECIFICATION forming part of Design No. 35,914, dated May 13, 1902.

Application filed April 21, 1902. Serial No. 104,053. Term of patent 7 years.

To all whom it may concern:

Be it known that I, WILLIAM T. SMITH, a citizen of the United States, residing in Philadelphia, Pennsylvania, have invented and produced a new and original Design for Fringe, of which the following is a specification.

My design for fringe is fully shown in the accompanying drawing, which represents sufficient of the fringe to illustrate the design, the remainder being merely a repetition of that which appears.

1 represents a corner portion of the article to which the fringe is applied, the same having a finish consisting of overedge-stitches 2. The fringe consists of intermeshed nettings 3, 4, and 5, this netting 3 being at the corner and the nettings 4 and 5 along the sides of

the article. Each netting terminates in a tassel 6, and between the nettings on the sides of the article are tassels 7.

Having thus described my invention, I claim and desire to secure by Letters Patent—

The design for fringe, substantially as described and as shown in the accompanying drawing.

In testimony whereof I have signed my name to this specification in the presence of two subscribing witnesses.

WILLIAM T. SMITH.
